UNITED STATES PATENT OFFICE

161,327

COMBINATION WATCH STAND AND JEWELRY HOLDER

Walter Freudenberg, Charleston, S. C.

Application April 11, 1950, Serial No. 9,122

Term of patent 3½ years

(Cl. D80—9)

To all whom it may concern:

Be it known that I, Walter Freudenberg, a citizen of the United States of America, and residing in the city of Charleston, county of Charleston, State of South Carolina, have invented a new, original, and ornamental Design for a Combination Watch Stand and Jewelry Holder, of which the following is a specification, reference being made to the accompanying drawing, forming part thereof.

Fig. 1 is a perspective view of the combination watch stand and jewelry holder, showing my new design;

Fig. 2 is a side view of the combination watch stand and jewelry holder, part of the jewelry holder being broken away and showing a sectional view thereof;

Fig. 3 is a front view of the watch stand, the lower part thereof and the jewelry holder being omitted.

I claim:

The ornamental design for a combination watch stand and jewelry holder, substantially as shown.

WALTER FREUDENBERG.
